UNITED STATES PATENT OFFICE.

PETER DE MATTIA, OF PASSAIC, NEW JERSEY, ASSIGNOR, BY MESNE ASSIGNMENTS, TO NATIONAL RUBBER MACHINERY COMPANY, OF AKRON, OHIO, A CORPORATION OF OHIO.

COLLAPSIBLE CORE.

Application filed June 21, 1923. Serial No. 646,890.

The present invention relates to collapsible cores used in the manufacture of shoes or castings for pneumatic tires, and has for its object to produce a collapsible core in which the 5 movable core sections are arranged to be successively moved into and out of a position of operative continuity, and to simultaneously impart to some of the movable sections a movement into and out of the plane of operative 10 continuity, and to provide means whereby such movements are accomplished by the manipulation of a single actuating device.

A further object is to so connect the sections of the core that the movable sections, while at 15 all times connected to each other and to the fixed section, shall nevertheless have the desired freedom of movement essential to producing a maximum collapsing of the core, and in the movement of the parts to place all of 20 the core sections in a position of operative continuity, the sections at this time forming a continuous annular core.

To the above ends the present invention consists of a collapsible core comprising a plurality of articulated sections, with means whereby said articulated sections are successively moved, a collapsible core in which the movable sections are moved spirally into and out of operative continuity and with relation to the 30 plane of operative continuity, and it further consists of the devices and combinations of devices which will be hereinafter described and claimed.

The present invention is illustrated in the 35 accompanying drawings, in which—

Fig. 1 shows a front elevation with the core sections in the position of operative continuity, and also in the plane of operative continuity.

Fig. 2 shows a sectional view taken on the line 2—2 in Fig. 1, parts being shown in elevation, and also illustrating in dotted lines the axial movement of the actuating device.

Fig. 3 shows a fragmentary sectional view, 45 parts being shown in elevation, and illustrating the connection between the operating device and the supporting spindle which produces the axial movement of the actuating device and the spiral movement of the articulated sections.

Fig. 4 shows a section taken on the line 4—4 in Fig. 3.

Fig. 5 is a front elevation, parts being shown in section, showing the core in operative continuity and in the plane of operative continuity. 55

Fig. 6 is a similar view illustrating the position of the parts at the initial collapsing movement, with one of the movable sections moved inward preliminary to this movement of the 60 other sections.

Fig. 7 illustrates the position of the parts when the movement of the movable sections has elevated the initial section and withdrawn the second section from the tire. 65

Fig. 8 shows a view similar to Fig. 7, when the second movable section has been moved to that extent which raises it out of the plane of the other sections, and has effected the withdrawal of the third movable section from the 70 tire.

Fig. 9 is a side elevation showing the parts in that position shown in Fig. 8.

Similar reference characters will be employed throughout the specification and drawings to designate corresponding parts. 75

The core comprises a plurality of segmental sections, 1, 2, 3 and 4, of such size and shape that when assembled as shown in Fig. 1, in alignment, they form a complete annulus, and 80 when thus assembled the parts are all in the same plane and in a position of operative continuity and also in the plane of operative continuity. The device also comprises a chuck 5 which is connected to a plate 6 by means of 85 the bolts 7, the plate 6 being adapted to be connected in any suitable manner to a jack or support not shown. The chuck 5 is provided with radial arms or brackets 8, to which the fixed section 1 is secured, as by means of the bolts 9. 90 This section 1 has no movement and of course always remains in the same position, and it is the movement of the other sections with relation to the fixed section 1 which causes the core to be expanded or collapsed. 95

The segmental section 2 is pivotally supported as at 10, to an ear 11 carried by the bracket arm 8, so that the section 2 has a movement about the pivot 10 towards and away from the axis or the center of the core, the 100 arrangement being such that it moves always in the plane of operative continuity when moved with relation to the position of operative continuity.

The segmental section 3 is pivotally connected as at 12 to a swiveled link 13 which is in turn pivotally connected at 14 to a stud 15, the arrangement being such that not only has the section 3 a pivotal movement about the pivot 12 toward and away from the center or axis of the core, with relation to the position of operative continuity, but it also has a pivotal movement about the pivot 14 at right angles to the pivot 12, so that the section 3 has a movement toward and away from the plane of operative continuity, and the combination or resultant pivotal action permits the section 3 to be moved in a spiral direction about the axis of the core.

The segmental section 4 is connected to the section 3 by a swiveled articulation like that just described, comprising a pivot 16, link 17, pivot 18 and stud 19, so that the section 4 likewise has a movement in and out of the position of operative continuity and with relation to the plane of operative continuity in a spiral direction, and because of the articulated and pivotal connections of the sections 2, 3 and 4, the movement of section 4 to collapse or expand the core will be imparted successively to sections 3 and 2, or it may be said that the sections move successively in train.

It is to be noted that the section 4 is the one to which the initial movement is imparted, and for this purpose it is provided near its free end with a swiveled stud 20 to which is pivotally connected at 21 a curved arm or link 22. The other end of the arm or link 22 is pivotally connected at 23 to crank arms 24 carried at the lower end of a tubular actuating device 25, which at its outer end is provided with a hand wheel 26, and which is mounted to be freely turned about and to move along a centrally disposed post 27 supported at the axis or central portion of the core by means of the chuck 5. The movement of this actuating device about the post 27 will of course, through the link 22, cause a successive movement of the movable sections into and out of the position of operative continuity, and a movement of the actuating device axially along the post 27 will impart to the movable sections 3 and 4 a movement with relation to the plane of operative continuity.

It will be noted that the joint or meeting faces of the sections 1 and 4, indicated by the numeral 28, extends tangentially, and that the joint 29 between the sections 1 and 2 also extends tangentially but at an angle to the joint 28, whereas the joints 30 and 31 between the sections 2 and 3 and 3 and 4 respectively, extend radially. This provides for a freedom of movement of the parts, as will be hereinafter described.

It is to be further noted that the pivotal and swiveled articulated connections of the movable sections are located upon or within the inner periphery of the sections which also insures a freedom of pivotal action and a

maximum collapsing movement of the movable sections with relation to the position of operative continuity. In the collapsing movement it is intended that the section 4 shall first be withdrawn from the tire by a pivotal movement in the plane of operative continuity only, so as not to distort the rubber by the movement of withdrawal, and for this purpose the tubular sleeve or actuating device 25 is provided with a stud 32 arranged to engage an annular groove 33 in the post 27. Engagement of the stud 32 with the annular groove 33 insures that the tubular sleeve 25 shall have a turning movement about the post sufficient to withdraw the section 4 from the tire before the spiral movement begins. This spiral movement is effected by means of a spiral groove 34 in the post 27 arranged to be engaged by the stud 32 and connecting with the annular groove 33, the arrangement being such that when the actuating device has been revolved to that extent permitted by the annular groove to withdraw the section 4 from the tire, the tubular sleeve 25 will then, because of the engagement of the stud 32 with the spiral groove 34, be moved outwardly along the post 27, whereby the section 4 will be moved spirally and inwardly about the post or sleeve, and because of the articulated swiveled connections between the sections 4 and 3 and 3 and 2, the section 3 will be withdrawn from the tire and moved spirally, and the section 2 will be withdrawn from the tire and moved about its pivot 10, and this movement is continued until the parts assume the position shown in Figs. 8 and 9, after which the tire can be stripped from the fixed section 1.

The arm 22 is angularly bent so that a considerable freedom of movement is provided before the arm comes in contact with the tubular actuating device 25, thus increasing to a considerable extent the inward movement of the section 4 before the section 3 is moved inwardly, and when in contact with the tubular actuating device, as shown in Fig. 6, the leverage or power is greatly increased and thus the withdrawal of the sections 3 and 2 by the power applied to section 4, is greatly facilitated because in this position the tubular actuating device forms a fulcrum about which the bent link 22 is moved.

It is to be noted that when in collapsed position the sections 3 and 4 are elevated above the plane of operative continuity so that the section 2 can be moved to a maximum extent in withdrawing it from the tire.

In operation, assuming the parts to be in the position of operative continuity and the plane of operative continuity, as shown in Fig. 1, a tire is built up thereon in the usual manner, and thereafter by revolving the hand wheel 26 the movable parts are withdrawn therefrom and the core collapsed by the inward and spiral movement of sections 3 and 4.

4, and the inward movement of section 2, so that the tire then supported on section 1 can be readily removed therefrom.

I claim:

5. In a collapsible core, a plurality of movable sections, swiveled articulations connecting the said sections, and means swiveled to one of said sections operable to move the said sections into and out of a position of operative continuity successively and in a spiral direction about the axis of the core.

10. In a collapsible core, a plurality of movable sections, a fixed section, and means to move the movable sections successively into and out of the position of operative continuity, one of said sections being pivoted with reference to the fixed section and having a movement in the plane of operative continuity only, and one of said sections being swiveled with reference to said pivoted section and having a movement in a spiral line into and out of the plane of operative continuity.

15. In a collapsible core, a plurality of movable sections, one of said sections being pivotally mounted for movement into and out of the position of operative continuity, and the other sections pivotally connected for movement into and out of the position of operative continuity, and also with relation to the plane 20 of operative continuity, an actuating device centrally disposed with relation to the core, and means connecting said actuating device to the free end of one of the movable sections whereby to impart movement to said sections 25 successively and in train.

30. In a collapsible core, a fixed section, a support therefor, a section pivoted to such

support, and a plurality of sections pivotally connected to the pivoted section and to each other for a pivotal motion in two directions, 40 a centrally disposed actuating device rotatably mounted, means to impart thereto an axial movement, a link pivotally connected to the actuating device to move therewith and a swiveled connection between the said link and 45 the free end of one of the movable sections.

5. In a collapsible core, a centrally disposed post, an actuating device mounted on the said post for rotary movement thereon and an axial movement along the said post, a 50 train of segmental core sections having a swiveled connection with each other and a swiveled connection with the actuating device, and means whereby a revolution of the actuating device will move the sections successively and in a spiral direction into and out of the position of operative continuity 55 and with relation to the plane of operative continuity.

6. In a collapsible core, a fixed section, a 60 plurality of movable sections, one of which is pivoted with reference to the fixed section, swiveled articulations connecting the said movable sections, an actuator mounted so as to be capable of rotation relative to the core, 65 and means responsive to the relative rotation of said core and actuator, for successively moving said swiveled articulated sections into and out of the position of operative continuity and into and out of the core plane, 70 said movable sections, when moved out of the position of operative continuity being spirally disposed with respect to the actuator.

PETER DE MATTIA.
